UNITED STATES PATENT OFFICE

PIERRE HAMELIN, OF MONTREAL, QUEBEC, CANADA

WINDOW CONSTRUCTION

Application filed July 10, 1930. Serial No. 467,066.

The present invention pertains to a novel window construction designed particularly for household use although suitable for other uses as well.

5 The principal object of the invention is to provide a window of the sliding sash type, and yet capable of being swung on a vertical axis inwardly of a room for cleaning purposes. Such adjustability of the window prevents the well known difficulties at present experienced in washing windows of the sliding sash type.

In keeping with this object, the sashes are so mounted that at least one vertical edge thereof is capable of a swivel movement with respect to the window frame. One edge of each sash is thus adapted to be swung entirely out of the frame, but is normally prevented from being swung by means of a 15 molding strip attached to the frame. When it is desired to swing the sashes for the purpose of cleaning them, the moldings are detached.

20 A further object of the invention is to provide means for supporting the sashes in the frame and preventing them from dropping when swung out of the frame. This means consists of latches carried by the sashes and adapted to enter grooves in the window 25 frames when the sashes are initially swung. The latches are so constructed that after subsequent swinging of the sashes, they remain 30 slidable in the grooves but cannot be withdrawn therefrom until the sashes are returned to normal or closed position.

35 A still further object of the invention is to provide an effective seal to prevent undesired leakage of air through the window structure, and also provide air pockets longitudinally of the sashes at the rounded ends.

The invention is fully disclosed by way of example in the following description and in the accompanying drawings, in which

Figure 1 is a plan section;

40 Fig. 2 is a plan section showing the sashes in elevation;

Fig. 3 is a detail plan section showing the sashes turned at an angle;

Fig. 4 is a detail vertical section;

50 Fig. 5 is a detail perspective view;

Fig. 6 is a sectional perspective view at one side of the sashes;

Fig. 7 is a similar view showing one of the sashes in locked position;

Fig. 8 is a sectional perspective view showing the keepers;

Fig. 9 is a sectional perspective view at the other side of the window frame;

Fig. 10 is still another sectional perspective view.

Reference to these views will now be made by use of like characters which are employed to designate corresponding parts throughout.

In Figures 1 and 2 is illustrated a window frame consisting of frame sections 1 and 2 fastened together at a tongue and groove joint 3. This joint stiffens the sides of the frame. In the frame sections 1 and 2 are formed vertical, arcuate grooves 4 and 5 respectively at both sides for the purpose of receiving window sashes 6 and 7 respectively 55 slidable therein. The ends of the sashes are rounded as at 8 to fit properly in the grooves and also to be swung on a vertical axis as 75 will presently appear. Between the sashes are provided molding strips 9 and 10 suitably shaped for engagement by the rounded ends 8. At the inner side of the sash 7 are also provided moulding strips 11 and 12 which 80 hold the sash in position.

The strip 12 is severed approximately midway between its ends as indicated by the numeral 13 in Fig. 9, thereby providing a removable lower section 12' normally held 85 in position by a screw knob 14. In like manner the intermediate molding strip 10 is also severed between its ends as indicated by the numeral 15 to provide a removable lower section 10' as shown in Fig. 9. The section 90 10' carries a plate 16 having offset ends 17 as shown in Fig. 5. These ends are receivable in a curved bracket 18 as shown in Fig. 10.

On the top of each of the sashes 6 and 7 95 is secured a plate 20 formed with a longitudinal boss or sleeve 21. Since these members are alike on both sashes, only one of them need be described. In each of the bosses is mounted a slide or latch 22 having at its 100

outer end a locking head or lug 23 and at its inner end a finger piece 24. The groove brackets 4 and 5 at this side of the window frame are grooved transversely at 25 (Figs. 2 and 3), and the grooves are of sufficient height to receive the locking heads 23. However, in the normal or closed position of the sashes as illustrated in Fig. 2, the heads are not in line with the groove and cannot be inserted therein.

Over the grooves is secured a plate 26 having slots 27 disposed over the grooves 25 and of less height than said grooves. One end of each slot, however, has an enlarged entrance or mouth 28 of sufficient size to receive the corresponding locking head 23.

In the operation of the device as thus far described, let it be assumed that the lower sash 7 is to be swung on a vertical axis into the room in order that both sides thereof may be washed. The lower detachable section 12' of the molding strip 12 is removed, whereupon the right hand end (Fig. 1) of the sash 7 may be swung away from the window frame. If the swinging movement were carried out to any considerable extent, there would be nothing to support this sash in the window frame. It will be seen, however, that a slight turning movement of the sash 7 brings the locking head 23 thereof into register with the enlarged mouth 28 of the corresponding slot 27. At this time the latch 22 is moved to insert the locking head 23 in the mouth 28, and continued swinging of the sash 7 brings the head 23 in the groove 25 behind the plate 26. The locking head is thus brought behind the narrower slot 27 and consequently cannot be released from the window frame until the sash is returned to its normal or closed position.

In order to swing the upper sash 6 in like manner, the lower sash 7 is first swung in the manner described, after lowering the sash 6, and the removable section 10' of the intermediate molding 10 is now withdrawn. It will be seen by an examination of Figs. 5 and 10 that the plate 16 may readily be withdrawn from the bracket 18 for this purpose. The slide 22 on the upper sash 6 now cooperates with the corresponding slot 27 and groove 25 in the manner already described in connection with the swinging of the lower sash.

The plate 26 is formed between its ends with a pair of horizontally curved ears 30 similar to the curved ends of the bracket 18 previously described. The intermediate molding 9 at the left hand side of the frame may also be severed midway between its ends as at 31 (Fig. 7) to provide a detachable lower section 9'. This section carries a detachable plate similar to the member 16 adapted for locking engagement with the ears 30. The removable section 9' may be withdrawn whenever desired to permit turning of

the sash 6 on its right hand end or to completely remove this sash if desired or necessary.

The plate 20 on the lower sash 7 is formed with a transverse boss 35 accommodating a sliding bolt 36. This bolt is adapted to enter an aperture 37 in the upper sash 6, as shown in Fig. 6, to lock the sashes together and thus lock the window in closed position.

At the rounded end, the sashes 6 and 7 are grooved longitudinally as at 38 to form air pockets 39. The ends of the sashes being rounded as at 8 to fit properly in the grooves 4 and 5 provide effective seal and prevents undesired leakage of air through the window structure. In the event of undesired air entering from both sides of the window, air pockets 39 will serve as mixing chambers for both air jets of different temperature. Undesired cold air draft from the outside is thus prevented.

For the purpose of reinforcing or stiffening the sashes 6 and 7, rigid metal strips 41 are passed vertically therethrough at the rounded ends as clearly shown in Figs. 1 and 4.

The sashes are balanced by sash weights, and from one of the weights extends a cord 42 secured to the right hand side of the lower sash 7 in the usual manner as indicated by the numeral 43 in Fig. 9. The cord 44 at the other side of the sash is anchored to an eyelet 46 formed as an integral part of the boss 21.

As stated in the introduction to this specification, it will be seen that the invention provides a durable window of the sliding sash type wherein the sashes may also be swung on vertical axes for cleaning purposes. Moreover, the construction enabling such swinging is simple, secure and effective. It will also be seen by reference to Fig. 2 that, because of the fact that the outer sash is narrower than the inner sash, the window opening diverges into the room and thus forms a diverging and increasing shaft of light entering the room from the exterior.

Although a specific embodiment of the invention has been illustrated and described, it will be understood that various alterations in the details of construction may be made without departing from the scope of the invention as indicated by the appended claims.

What I claim is:—

1. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, and latching means carried by said sashes and slidably entering said frame to prevent total detachment of said sashes from said frame.

2. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, latching means carried by said sashes and slidably entering said frame to prevent total detachment of said sashes from said frame, and grooves longitudinally in the ends of said sashes and forming air pockets for mixing different possible air jets from both sides of said window sashes. 70
- 5 3. In a window construction, a window frame, sashes vertically slidable therein, molding strips retaining said sashes, said strips being partially removable to permit one edge of each sash to be swung out of said frame, the remaining edge of each sash having a pivotal mounting in said frame, a latch slidably on each sash, said window frame being grooved transversely to slidably receive said latches, whereby to prevent total detachment of said sashes from said frame. 75
- 10 4. In a window construction, a window frame, sashes vertically slidable therein, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved transversely to slidably receive said heads, a plate secured over said grooves and having slots narrower than said grooves, said slots having enlarged mouths adapted to receive said locking heads, whereby said heads may be swung into said grooves and retained by said slots to prevent total detachment of said sashes from said frame. 80
- 15 5. In a window construction, a window frame, sashes vertically slidable therein, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved transversely to slidably receive said heads, a plate secured over said grooves and having slots narrower than said grooves, said slots having enlarged mouths adapted to receive said locking heads, whereby said heads may be swung into said grooves and retained by said slots to prevent total detachment of said sashes from said frame. 85
- 20 6. In a window construction, a window frame, sashes vertically slidable therein, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved transversely to slidably receive said heads, a plate secured over said grooves and having slots narrower than said grooves, said slots having enlarged mouths adapted to receive said locking heads, whereby said heads may be swung into said grooves and retained by said slots to prevent total detachment of said sashes from said frame. 90
- 25 7. In a window construction, a window frame, sashes vertically slidable therein, molding strips retaining said sashes, said strips being partially removable to permit one edge of each sash to be swung out of said frame, the remaining edge of each sash having a pivotal mounting in said frame, latching means carried by said sashes and slidably entering said frame to prevent total detachment of said sashes from said frame, and stiffening members mounted longitudinally in the ends of said sashes. 95
- 30 8. In a window construction, a window frame, sashes vertically slidable therein, molding strips retaining said sashes, strips being partially removable to permit one edge of said sash to be swung out of said frame, the remaining edge of each sash having a pivotal mounting in said frame, latching means carried by said sashes and slidably entering said frame to prevent total detachment of said sashes from said frame, and a locking bolt carried by one of said sashes and adapted to enter the other sash. 100
- 35 9. In a window construction, a window frame, sashes vertically slidable therein, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved transversely to slidably receive said heads, a plate secured over said grooves and having slots narrower than said grooves, said slots having enlarged mouths adapted to receive said locking heads, whereby said heads may be swung into said grooves and retained by said slots to prevent total detachment of said sashes from said frame, said locking heads being out of register with said mouths when said sashes are in closed position. 105
- 40 10. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 110
- 45 11. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 115
- 50 12. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 120
- 55 13. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 125
- 60 14. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 130
- 65 15. In a window construction, a window frame, sashes vertically slidable therein, said sashes having rounded vertical ends receivable in arcuate grooves in said sashes, molding strips retaining said sashes, said strips being partially removable to permit one edge of each sash to be swung out of said frame, the remaining edge of each sash having a pivotal mounting in said frame, a latch slidably carried by each sash and having a locking head, said window frame being grooved 135

transversely to slidably receive said heads, a plate secured over said grooves and having slots narrower than said grooves, said slots having enlarged mouths adapted to receive said locking heads, whereby said heads may be swung into said grooves and retained by said slots to prevent total detachment of said sashes from said frame, said locking heads being out of register with said mouths when said sashes are in closed position.

In witness whereof I have hereunto set my hand.

PIERRE HAMELIN.
